UNITED STATES PATENT OFFICE.

LEON W. CAMPBELL, OF WOONSOCKET, RHODE ISLAND, ASSIGNOR OF ONE-HALF TO MALCOLM CAMPBELL, OF BOSTON, MASSACHUSETTS.

LOOM-SHUTTLE.

SPECIFICATION forming part of Letters Patent No. 659,485, dated October 9, 1900.

Application filed November 17, 1899. Serial No. 737,268. (No model.)

To all whom it may concern:

Be it known that I, LEON W. CAMPBELL, of Woonsocket, in the county of Providence and State of Rhode Island, have invented certain new and useful Improvements in Loom-Shuttles, of which the following is a specification.

This invention has relation to loom-shuttles, its object being to provide certain improvements therein for threading the filling 10 through the eye.

Heretofore it has been the common practice for a weaver in threading the eye to place the thread in proximity to the inner end of the eye and by placing his lips at the eye and 15 violently inspirating to draw the thread through it. As there is constantly more or less lint and dust in the shuttle and in the eye, such foreign matter is sucked into the throat and lungs, with the result of impairing 20 the health, if not finally causing the loss of life of the weaver. Attempts have been made to remedy this evil by carrying the eye or aperture entirely through the shuttle, so that the weaver may blow from the opposite 25 side of the shuttle, and thus prevent the lint from being drawn into the lungs. This attempt has been generally unsuccessful, owing to the awkward position in which the weaver had to hold the shuttle, in addition 30 to the time required to reverse the shuttle to bring the aperture to the lips. According to my invention, however, I provide for the weaver drawing the thread through the eye by inducing a current of air therethrough, 35 this current of air being caused by blowing through an aperture leading from the side of the shuttle in which the eye is placed and communicating with the eye-aperture, as shall now be explained in detail.

40 Referring to the drawings forming a part of this specification, Figure 1 represents in perspective view a shuttle equipped with my invention. Fig. 2 represents in plan view the eye end of the shuttle. Fig. 3 represents 45 a horizontal section of the same. Fig. 4 represents a section on the line 4-4 of Fig. 3.

The shuttle can be made after any suitable pattern, its shape or style being immaterial. As shown, it carries the spindle 1 for the cap 50 2 and is formed on its front side with the usual groove 3 to prevent the thread from be-

ing severed as the shuttle is driven through the shed. At the end of the shuttle are bored two holes, apertures, or ducts 4 5, which coincide at their inner ends, forming the two 55 sides of a triangle. The hole 4 is carried through the usual chamber 6, which is formed in the shuttle to receive the finger of the weaver as he places the loose end of the filling at the end of the eye-aperture, said chamber 60 communicating with the interior of the shuttle by a duct 7. In the outer end of the aperture 4 is placed a shell or bushing 8, which extends part way into the chamber 7, and in the inner end of said aperture is fitted an 65 ejector-nozzle 9, having a contracted outlet. The hole 4, with the bushing 8, constitutes the eye for the filling, which will be drawn through it when a blast of air is blown into the aperture 5. The air passes from the last-men- 70 tioned aperture through the ejector 9 and induces such a current of air from the chamber 6 through the eye that when the thread is placed in said chamber it will be carried through the eye instantly, even though it is 75 some little distance from the inner entrance to the bushing. By boring the aperture from the side of the shuttle in which the eye is located the weaver is not compelled to reverse the shuttle, and the operation of threading 80 the eye is performed without loss of time and with little or no exertion.

By exhaling the breath in drawing the thread through the eye instead of inhaling it the weaver does not breathe into his lungs 85 and bronchial tubes lint, dust, or other foreign material to the detriment of his health.

Having thus explained the nature of my invention and described a way of constructing and using the same, though without attempt- 90 ing to set forth all of the forms in which it may be made or all of the modes of its use, what I claim, and desire to secure by Letters Patent, is—

1. A shuttle having a thread-eye on the side 95 thereof, and a supplemental passage leading from the side mentioned for permitting the induction of a current of air through said eye.
2. A shuttle having two converging apertures communicating with each other and 100 opening on the same side, one forming a thread-eye and the other serving for the in-

duction of a current of air through the first-mentioned aperture.

3. A shuttle having a thread-eye, an ejector located in the rear of said eye, and a duct 5 leading to said ejector for admitting air thereto, said duct having its inlet at the side of the shuttle in which the eye is located.

4. A shuttle having two ducts leading inward from the same side and communicating 10 at their inner ends, a thread-chamber com-

municating with one of said ducts, and an ejector located at the inner end of the last-mentioned duct.

In testimony whereof I have affixed my signature in presence of two witnesses.

LEON W. CAMPBELL.
